UNITED STATES PATENT OFFICE.

SAMUEL G. GREEN, OF GRAY, GEORGIA.

MACHINE-GUN UNIT.

Application filed January 18, 1926. Serial No. 82,121.

(GRANTED UNDER THE ACT OF MARCH 3, 1883, AS AMENDED APRIL 30, 1928; 370 O. G. 757.)

The invention described herein may be manufactured and used by or for the Government for governmental purposes without the payment to me of any royalty thereon.

5 This invention relates to a machine gun unit and particularly it has reference to a sear release mechanism applicable for synchronized guns mounted on aircraft.

In mechanisms of the above type, commonly known as trigger motors, the amount of power required to trip the sear is considerable even in the standard .30 caliber guns and this is especially true when the release of the sear is accomplished by a transversely sliding member. As a consequence, the mechanism is unreliable in operation and requires frequent readjustment.

10 In devising an improved trigger motor, particular attention has been directed to producing a mechanism which will be especially applicable to machine guns of large caliber, for example the .50 caliber gun, now being extensively used to supplant the standard sized weapon.

25 The principal objects of this invention then are: to provide a more accurate and dependable sear release mechanism operable on application of only a slight force or power and positive in its semi-automatic action; to simplify the arrangement by establishing direct connection with the sear thereby avoiding linkage with its consequent lost motion and backlash; to employ novel means traveling a minimum distance for assuring clearance when the bolt of the gun arrives in battery out of time with the trigger; and, to increase the accessibility for connection with the motor of the airplane.

To these and other ends, my invention consists in the construction, arrangement and combination of elements, described hereinafter and pointed out in the claims forming a part of this specification.

30 A practical embodiment of my invention is illustrated in the accompanying drawings, wherein:

Fig. 1 is a more or less diagrammatic view showing the relation between the gun and motor;

35 Fig. 2 is a longitudinal sectional view taken through the sear release mechanism, the sear being shown in elevated or engaged position;

Fig. 3 is a view in rear elevation of the bolt in battery showing the normal position of the trigger head during reciprocation;

Fig. 4 is a longitudinal sectional view showing the position assumed by the trigger head when depressed to disengage the sear;

Fig. 5 is a view in end elevation of Fig. 4;

Figs. 6, 7 and 8 are detail plan views showing various positions of the trigger head and sear;

Figs. 9, 10 and 11 are corresponding detail views in elevation, and

Fig. 12 is a perspective of the trigger head.

Referring to the drawing by numerals of reference:

There is shown at 5 the receiver of a machine gun in which reciprocates the bolt 6 carrying the firing pin 7 which is cocked in the well known manner by the lever 8. The pin is held in cocked position by a sear 9 slidable vertically in slots 6^a cut in the rear face of the bolt and forced to pin engaging position by a spring 10.

The trigger or sear release mechanism is mounted in the cover or top plate 5^a of the receiver directly above the position assumed by the sear when the bolt is in battery. It consists essentially of a vertically reciprocable rod or trigger 11 provided on its lower extremity with a striker head 12 which in the preferred embodiment of the invention is fast to the rod, being shown integral therewith. The mounting of the trigger may be of any suitable character, a simple form being shown, which comprises a support in the form of a cylindrical casing 13 one end of which is reduced as at 13^a to provide an annular shoulder 13^b whereby when the casing is inserted through an aperture 5^b in the top plate it may be securely clamped in position by means of a cap nut 14 threaded on the reduced portion which extends through the plate. The cap nut is formed with an aperture 14^a to receive the upper portion of the trigger 11. A spring 15 encircling the trigger and confined between the base of the casing and a collar 16 on the trigger normally maintains the trigger in the raised position, the collar by engaging the cap nut serving to limit the action of the spring while a pin 17 in the trigger exterior of the cap nut limits the downward stroke of the trigger when the same is actuated by the cam 18 on

the shaft 19 connected to the motor. The spring 15 is further anchored to the casing and trigger to impart rotational movement to the trigger and restore the striker head 12 to operative or armed position when the same has been displaced, as will presently be described. If desired, the striker head can be rotatably carried by the trigger rod and have independent means for restoring it.

10 The casing 13 is provided at its lower extremity with an extending finger 20, which, as shown in Fig. 3, is positioned at one side of the path of travel of the sear 9 and engages the tooth 12^a on the striker head to limit the rotational movement of the trigger under the torsional action of the spring and thus hold it in operative position during reciprocation with its tooth 12^b in line with the sear.

15 20 In operation, should the trigger be in the lower or striking position when the bolt arrives in battery, the sear during its final movement will strike the tooth 12^b thereby rotating the trigger. The trigger is immediately counter rotated by the spring 15 and accordingly restored to operative position so that on the succeeding downward stroke it will strike the sear to disengage it from the firing pin. It is to be noted that in providing clearance for the sear in this manner the movement of the trigger head is in the approximate direction of travel of the sear and consequently requires but a minimum displacement of the striker head.

25 30 35 Unlike those types of trigger motors which employ a slide carried by the bolt, there is no element in the present mechanism which will impede or increase the load on the sear spring or be liable when disarranged to automatically trip the sear on return of the bolt into battery. Should the spring 15 in the present device be broken and the trigger remain in the lowered position, the gun will not "run away" as the trigger will be rotated by the sear to inoperative position where it will remain. Moreover, the simplicity of arrangement and the ease of operation make for accuracy and dependability.

40 The connection as shown between the gun and the motor is illustrative only as it is apparent that by reason of the accessible mounting of the trigger in the top plate of the receiver the connection is capable of innumerable variations.

45 50 55 While in the foregoing there has been illustrated and described such combination and arrangement of elements as constitute the preferred embodiment of the invention, it is nevertheless desired to emphasize the fact that interpretation of the invention should only be conclusive when made in the light of the subjoined claims.

I claim:

1. In a machine gun unit, a receiver, a reciprocal breech bolt therein, a firing pin

carried thereby and movable with respect thereto, means for cocking the pin, a vertically movable sear for holding the pin in cocked position, a casing secured to the top plate of the receiver and depending therefrom, a trigger rod mounted vertically in the casing, a striker head on the lower end of said trigger, a spring for normally holding the trigger in raised or inoperative position, said spring also adapted to rotate the trigger and maintain the striker head in armed position, means for intermittently depressing the trigger, and means for limiting both reciprocal and rotational movement of the trigger.

2. In a machine gun unit a reciprocal breech bolt, a firing pin carried thereby and movable with respect thereto, means for cocking the pin, a vertically movable sear for holding the pin in cocked position, a trigger rod adapted to be mounted vertically above the sear, a striker head on the lower end of said trigger, a spring for normally holding the trigger in raised or inoperative position, said spring also adapted to rotate the trigger to maintain the striker head in armed position, and means for limiting rotational movement of the trigger.

3. In a machine gun unit, a reciprocal breech bolt, a firing pin carried thereby and movable with respect thereto, means for cocking the pin, a vertically movable sear for holding the pin in cocked position, a trigger rod adapted to be mounted vertically above the sear, a striker head on the lower end of said trigger capable of rotational movement, means for reciprocating the trigger, and one of said reciprocal means adapted to restore the striker head to armed position when the same has been displaced by the sear.

4. In a machine gun unit, a reciprocal breech bolt, a firing pin carried thereby and movable with respect thereto, means for cocking the pin, a vertically movable sear for holding the pin in cocked position, a trigger rod adapted to be mounted vertically above the sear, a striker head on the lower end of said trigger capable of rotational movement, means for reciprocating the trigger, and means for restoring the striker head to armed position when the same has been displaced by the sear.

5. In a machine gun unit, a reciprocal breech bolt, a firing pin carried thereby and movable with respect thereto, means for cocking the pin, a sear for holding the pin in cocked position, a rectilinearly movable trigger rod for engaging the sear, means for reciprocating the rod, and a striker head on the rod movable in the direction of travel of the sear in providing clearance for said sear.

6. In a machine gun unit, a reciprocal breech bolt, a firing pin carried thereby and

movable with respect thereto, means for cocking the pin, a sear for holding the pin in cocked position, a rectilinearly movable trigger rod for engaging the sear, means for reciprocating the rod, and a striker head on the rod movable a minimum distance in providing clearance for said sear.

7. In a machine gun unit, a reciprocal breech bolt, a firing pin carried thereby and movable with respect thereto, means for cocking the pin, a sear for holding the pin in cocked position, a rectilinearly movable trigger rod for releasing the sear, means for reciprocating the rod, and said rod adapted to be axially rotated by the sear in providing clearance therefor.

8. In a machine gun unit, a reciprocal breech bolt, a firing pin carried thereby and movable with respect thereto, means for cocking the pin, a sear for holding the pin in cocked position, a rectilinearly movable trigger rod for engaging the sear, means for reciprocating the rod, and said rod adapted to be moved by the sear to unarmed position.

25 9. In a machine gun unit, a reciprocal breech bolt, a firing pin carried thereby and movable with respect thereto, means for cocking the pin, a sear for holding the pin in cocked position, a rectilinearly movable sear engaging trigger rod, and means for reciprocating the rod.

10. In a machine gun unit, a receiver, a reciprocal breech bolt therein, a firing pin carried thereby and movable with respect thereto, means for cocking the pin, a sear for holding the pin in cocked position, and a vertically reciprocal trigger mounted in the top plate of the receiver.

11. In a machine gun unit, a receiver, a reciprocal breech bolt therein, a firing pin carried thereby and movable with respect thereto, means for cocking the pin, a sear for holding the pin in cocked position, a support extending within the receiver, means for clamping said support to the receiver and sear actuating means mounted in said support.

12. In a machine gun unit, a receiver, a reciprocal breech bolt therein, a firing pin carried thereby and movable with respect thereto, means for cocking the pin, a sear for holding the pin in cocked position, a support

extending within the receiver and sear actuating means mounted in said support.

13. In a machine gun unit, a receiver, a reciprocable breech bolt therein, a firing pin carried thereby and movable with respect thereto, means for cocking the pin, a sear for holding the pin in cocked position, a vertically disposed support in the top plate of the receiver and extending on both sides thereof and a sear actuating means mounted in said support.

14. In a machine gun unit, a firing mechanism, a sear therefor, a rectilinearly movable sear actuator and means adapted to be operated from a distance for directly actuating said sear actuator.

15. In a machine gun unit, a firing mechanism, a sear therefor, a one piece sear actuator mounted for yielding movement when struck by the sear, and means adapted to be operated from a distance for directly operating said sear actuator.

16. In a machine gun unit, a reciprocating sear, a rectilinearly movable sear actuator directly engaging the sear, a cam member engageable with said actuator and a motor driven shaft for rotating the cam member.

17. In a machine gun unit, a sliding sear and a rectilinearly movable impulse receiving member directly engageable with the sear.

18. In a machine gun unit, a receiver, a reciprocable breech bolt therein, a firing pin carried thereby and movable with respect thereto, means for cocking the pin, a sear for holding the pin in cocked position and a sear release member mounted for rectilinear movement and extending through the top plate of the receiver.

19. The combination with a firing mechanism including a sear, and a source of synchronous power associated therewith, of a single sear tripping element interposed between the sear and source of power.

20. The combination with a breech bolt including a sear, of a sear tripping element rotatable about its longitudinal axis when in sear tripping position by the sear when in normal position, as the bolt returns to breech closing position.
